UNITED STATES PATENT OFFICE

2,512,515

POSTER PANEL

Alexander L. Bauers and Max Rosner, Chicago,
Ill., assignors to General Outdoor Advertising
Co., Inc., a corporation of New Jersey

Application March 29, 1945, Serial No. 585,510

11 Claims. (Cl. 40—125)

1

This invention relates to an advertising display structure or poster panel commonly called a billboard, and has for its object the provision of an advertising display structure in which the display panel may be lowered and swung from its display position into a servicing position below and in front of the display position. Specifically the invention relates to a structure which has the functions and appearance of a conventional billboard and in which the display panel can be lowered and swung from its display position within a limited space in front of the billboard.

A further object of the invention is to provide a poster panel with a removable display panel which may be easily and simply constructed and operated without any special tools or equipment to facilitate the replacement of the poster upon the poster panel.

Another object of the invention is to provide a poster panel upon which the poster may be replaced without the liability of exposing the border of the display panel to defacement or soiling by the paste or adhesive which is generally used when paper posters are applied to the display panel, or paint when the poster is painted on the panel.

In conventional poster panel construction a display panel is mounted upon suitable framework and surrounded by an appropriate border to display an advertisement upon the display panel. The display material exposed upon the display panel is designed for display only a short time, that is for a month or a few months, and is then replaced either by painting a new display upon the panel or by affixing new posters to the panel by means of adhesive or other means of attachment. Not infrequently three-dimensional displays are secured to the display panel and similarly removed and replaced after the desired time of display.

In order to replace the display upon the display panel it has been necessary to provide scaffolding or other means of access to reach the display panel, as the panel was usually constructed as a stationary part of the poster panel structure and mounted at some height above the ground in order to make the display more conspicuous and more widely visible.

Both because of the size of the display panels customarily used and the large posters used thereon, the problem of applying the posters or painting displays upon the panel while in its elevated normal display position presented a substantial problem. Even with the use of scaffolding and long handled brushes the problem was

2

one of some difficulty, the operation was awkward, and frequently where paint or adhesive was used the border about the display panel was soiled and disfigured by inevitable splashing and dripping of the paint or adhesive.

As the location in which a poster panel can be mounted is usually determined by considerations of visibility and traffic, frequently the best location for display purposes requires that the 10 poster panel structure be mounted upon a wall or in a location where the space before the panel is quite limited. Occasionally the lack of license to approach the panel except within a few feet of its foundation rendered the panel inaccessible 15 to the use of long handled brushes and precluded the construction of scaffolding to obtain access to the display.

The poster panel of this invention is one 20 designed to permit the display panel to be lowered from its display position to an intermediate position and then, in a continuing movement, to be swung a short distance in front of the poster panel structure while it is being lowered further to the base of the poster panel structure. The 25 display panel is thus delivered to a readily accessible servicing position and the operator can reach its entire area for removal of the discarded display and its replacement.

In this servicing position the problem of controlling the application of paint and adhesive 30 without splashing it upon parts of the structure that might thereby be soiled is also obviated. This enables the replacement of the display without each time requiring the renewal or refinish- 35 ing of the border.

These and other features of the invention will be seen from the following detailed specification read in connection with the accompanying drawings forming part thereof, in which—

40 Figure 1 is a view in perspective of a preferred form of the invention secured to a building wall with the movable display panel in its lowered servicing position;

Fig. 2 is a vertical section taken on the line 45 2—2 of Fig. 1;

Fig. 3 is a vertical section corresponding to that shown in Fig. 2 with the display panel in its upper or display position;

Fig. 4 is a fragmentary vertical section showing a preferred manner of securing the movable display panel to the moving frame upon which it is supported;

Fig. 5 is a fragmentary vertical section of the lower edge of the movable display panel showing 55 a preferred manner of locking the movable dis-

play panel in its display position to prevent displacement;

Fig. 6 is an elevation of half of the structure shown in Fig. 1 with the movable display panel in display position;

Fig. 7 is an elevation of half of the structure shown in Fig. 1 with the movable display panel in lowered or servicing position;

Fig. 8 is a horizontal section of the structure shown in Fig. 7 taken on the line 8-8 of Fig. 7;

Fig. 9 is a fragmentary vertical section showing a detail of the pivoted arms which support the moving frame upon which the movable display panel is mounted;

Fig. 10 is a fragmentary horizontal section of the guide rollers on the upper end of the pivoted arms taken on the line 10-10 of Fig. 9; and

Fig. 11 is a fragmentary vertical section taken on the line 11-11 of Fig. 1 showing the side molding support bracket.

Referring to the drawings, the poster panel structure of this invention comprises substantially four sub-assemblies which will be separately described in the following specification.

These sub-assemblies are:

- A, the molding or display panel border;
- B, the movable display panel;
- C, the movable display panel frame; and
- D, the stationary supporting structure to support and guide the movable display panel frame.

A. Molding or display panel border

While the invention is shown applied to a wall 20, it is readily applicable, without affecting its principle, to a stationary framework of the familiar type employed in this art. Secured to the wall is the border or molding about the display panel shown in this preferred form comprising the upper molding 22, the lower molding 24, and the side moldings 26. These are preferably made in separate parts and attached as hereinafter described. To complete the molding it can more easily be made as shown in Fig. 6 where the corners 28 are made separately and applied after the other members of the border are installed.

The upper molding is secured to the frame member 82 against vertical displacement by means of the upper molding clips 30 (Fig. 4), and against lateral displacement by the clips 29 (Figs. 2, 6). The clips 30 are permanently secured to the frame member 42 and the upper molding 22 is made with a flange which can be slipped under the clip 30 and then held in position by means of the locking pins 31 (Fig. 4).

Similarly the lower molding can be secured to the frame members 82 by employing a structure practically identical with that of the upper molding and hanging the flanged molding over the lower molding rail 32 which is in the form of an angle iron and bolted to the frame member 82.

The side molding members 26 are secured similarly by means of side molding clips 34 which are secured to the side molding and slid over the side molding support rail 38 (shown in Figs. 6 and 11) which is supported on the side molding bracket 36 which is secured to the wall 20 or to a suitable framework if the billboard is supported by a framework instead of a building.

With these elements designed as indicated the upper molding can be slid into place and locked there by the locking pins 31, the lower molding then locked into position by means of the rails 32, and the side moldings slid into place and

supported by the clips 34. If the molding members are cut in the manner indicated in Figs. 6 and 7, they will, for facility of installation, be made without the corner members 28 which can subsequently be secured to the molding to complete the border A.

The border may be made of sheet metal lumber, or composition materials. Sheet metal lends itself most readily to fabrication into pleasing forms and the structure shown is so constructed although obviously the principle of the invention is not dependent upon the use of any particular materials.

B. The movable display panel

Within the border A is mounted the movable display panel B upon which the display is painted, posted, or, if three dimensional, mounted. It is this portion of the structure that requires frequent renewal and presents the problem to which this invention is addressed.

As shown in the accompanying drawings the movable display panel has a face 40 which may be constructed of sheet metal, wood, composition board or any other suitable material upon which the desired display can be secured.

In the preferred embodiment shown the face of the panel is shown in the form of sheet metal. To the back of the face 40 are secured the support clips 42 (Figs. 4, 8, 9, 10) by which the display panel face 40 can be demountably secured to the movable display panel frame C and locked thereto by means of the locking pins 46 (Figs. 4, 9, 10).

In order to insure that the display panel is securely held in its display position adjacent the border, the display panel is fitted with locking clips 44 (Fig. 5) near the lower edge of the display panel, by means of which the panel can be hooked to the hooks 90 to prevent displacement of the lower edge of the panel when in display position.

The demountable features of construction shown in the accompanying drawings and incorporated in the embodiment of this invention are not claimed in this application but will be separately claimed in a divisional application to be filed hereafter.

C. The movable display panel frame

The movable display panel 40 is secured to a movable display panel frame C. This frame is probably best shown in the sectional views of the accompanying drawings (Figs. 2 and 3). The frame is constructed of the horizontal frame members 50 and the vertical frame members 52 to which the display panel is secured, as best shown in Figs. 2 and 9 by means of the display panel support clips 42 and the locking pins 46.

Pivoted secured to the frame are the arms 54 (Figs. 2 and 9). At the upper end these arms are pivoted to the frame member 52 and are provided with the guide rollers 56 (Fig. 10). The lower ends of these arms are free and provided with the pivot rollers 58 rotatably mounted on the bolts or pins. Secured to the movable frame C is the cable or chain 60 by which the movement of the frame is controlled. One end of the cable 60 is attached to a suitable counterweight 62 or may, if desired, be wound upon a sheave (not shown).

If the counterweight is used it can extend over a substantial part of the breadth of the display panel and in order to insure its even movement and to prevent unnecessary swinging of the counterweight, it may be provided with the

counterweight guide hooks 64 (Figs. 1 and 7) which are freely guided by means of the guide rails 66.

D. Stationary supporting structure

In order to support and guide the movable display panel frame C, the poster panel structure of this invention has a suitable stationary framework comprising the I-beams or vertical frame members 82 which are supported on the wall 20, or other framework by means of the I-beam support brackets 80. The I-beams are cut at 84 to form interruptions in the front rail of the beams so that the guide rollers 56 on the pivoted arms 54 may escape from the track formed by the forward rail of the I-beams in the operation of the movable frame.

Secured to the rear of the I-beams are suitable trunnions 86 designed to receive the pivoted arm pivot rollers 58 which can pivot within the trunnions. Pulleys or sprockets 88 are secured near the upper end of the I-beams to guide the cable or chains 60 in the operation of the structure.

Finally, the stationary structure is provided with the locking hooks 90 shown secured to the lower molding 24 or the lower molding rail 32 (Fig. 5). These hooks are designed to enter holes cut in the locking clips 44 secured to the rear of the display panel face 40 near the lower edge thereof.

Operation of the poster panel structure

The movable display panel B is shown in its lowered or servicing position in Fig. 1 and sectionally in Fig. 2, while the structure is shown with the display panel in display position in Fig. 3.

With the parts in the relative positions shown in Fig. 3, the movable display panel can be unlatched from the locking hooks 90 merely by lowering the display panel. It may be pulled downwardly or the counterweight lifted and the display panel will move in its own plane downwardly and be held in that plane by the guide rollers 56 which are restrained by the front rails of the I-beams 82. As the display panel B and the movable frame C move downwardly the pivoted arms 54 also move downwardly until their free ends, upon which the above rollers 58 are mounted, fall into the trunnions 86. As they do so the pivot arm guide rollers 56 escape from the restraint of the front rails of the I-beams 82 through the interruptions 84 in those rails through which the guide rollers 56 may pass.

As the pivot rollers 58 encounter the trunnions 86 further downward movement is halted and the movable display panel and frame are swung forward upon the pivots 58 in the trunnions 86, as best shown in Fig. 2. The display panel can thus be brought into a position below and a short distance in front of the display panel border.

In this servicing position (Fig. 2) the operator can readily replace any display matter upon the display panel or actually remove the panel itself by removing the locking pins 46 which lock the display panel face 40 to the removable frame C.

When the servicing of the display panel has been completed the counterweight 62 may be pulled down or the display panel 40 lifted and the movements heretofore described, reversed. The display panel will pivot about the pivot rollers 58 in the trunnions 86 until the display panel is

returned to approximately the plane of its display position whereupon the guide rollers 56 will reenter the I-beam guides through the interruptions 84 in the front rails of the I-beams when further upward movement of the display panel will restore it to its display position.

As the display panel is drawn into its final position the locking clips 44 will engage the locking hooks 90 secured to the stationary structure 10 and the lower edge of the display panel thus held against displacement.

If desired, suitable handles can be fitted to the display panel or to the counterweight and suitable locking devices provided to prevent the unlicensed movement of the display panel.

Having thus shown and described one embodiment of the invention, it is to be understood that it is capable of many modifications. Changes, therefore, in the construction and arrangement 20 may be made without departing from the spirit and scope of the invention as disclosed in the appended claims, in which it is intended to claim all novelty inherent in the invention as broadly as permissible, in view of the prior art.

25 We claim:

1. A poster panel comprising a stationary border, a supporting structure for the stationary border, a movable frame, a display panel detachably carried by the movable frame, and means 30 connecting the movable frame and the supporting structure to carry the display panel from a display position adjacent the border to a servicing position below and in front of the border.

2. A poster panel comprising a stationary border, a movable frame, a display panel carried by the movable frame, a stationary supporting structure to support the stationary border and to support and guide the movable frame, and means connecting the movable frame and stationary supporting structure including pivot means movable in relation to the supporting structure by which the movable frame and display panel can be moved vertically with respect to the border from display position and swung 45 in front of the border into servicing position.

3. A poster panel comprising a stationary border, a movable frame, a display panel carried by the movable frame, a stationary supporting structure to support the stationary border and 50 to support and guide the movable frame, and a plurality of arms pivotally secured at one end to the movable frame and at the other end having pivots movably engageable with the supporting structure to permit the movable frame and display panel to be first lowered from display 55 position adjacent the border and then swung forward into servicing position in front of and below the display position.

4. A poster panel comprising a stationary border, a movable frame, a display panel carried by the movable frame, a stationary supporting structure to support the stationary border and to support and guide the movable frame, a plurality of vertical rails in the supporting structure, 65 a plurality of arms pivotally secured at one end to the movable frame, guide rollers on the arms moving vertically along the vertical rails, and trunnions upon the vertical rails to receive the other ends of the arms for pivotal movement 70 therein.

5. A poster panel comprising a stationary border, a movable frame, a display panel carried by the movable frame, a stationary supporting structure to support the stationary border and 75 to support and guide the movable frame, vertical

guide rails in the supporting structure, interruptions in the guide rails, trunnions secured to the guide rails, a plurality of arms at one end pivoted to the movable frame and at the other swingable in the trunnions, and means to lower the movable frame and the arms until the latter rest in the trunnions whereby the arms and movable frame are freed for swinging movement by the interruptions in the guide rails.

6. A poster panel comprising a stationary border, a movable frame, a display panel carried by the movable frame, a stationary supporting structure to support the stationary border and to support and guide the movable frame, vertical guide rails in the supporting structure, a plurality of arms pivotally secured at one end to the movable frame and having free lower ends, guide rollers on the arms moving along the guide rails, interruptions in the guide rails whereby the guide rolls may be freed therefrom, trunnions secured to the guide rails to receive the free end of the arms, and means to lower the movable frame and the arms in a vertical plane fixed by the guide rails until the free ends of the arms engage the trunnions and then to swing the arms freed by the interruptions in the guide rails and the movable frame and display panel to a servicing position in front of and below the border.

7. A poster panel comprising a stationary border, a movable frame, a display panel demountably secured to the frame and carried thereby, a stationary supporting structure for the stationary border, and means connecting the removable frame and the stationary supporting structure by which the movable frame and display panel are movably supported and guided by the supporting structure so that the display panel can be lowered from a display position adjacent the border to a lower position in the same vertical plane and then swung into a position still lower and in front of the border.

8. A poster panel comprising a stationary border, a movable display panel, a stationary supporting structure for the stationary border, a plurality of arms pivotally secured at one end to the display panel and vertically movable with relation to the supporting structure, and a plurality of trunnions in the supporting structure to receive the other ends of the arms to arrest their downward vertical movement and to swing the arms and display panel outwardly and below the border.

9. A poster panel comprising a stationary border, a supporting structure for the stationary

border, a movable frame, a display panel mounted thereon and carried thereby for the stationary border, a stationary supporting structure, a plurality of arms pivotally secured at one end to the movable frame and free at the other end, a plurality of trunnions in the supporting structure to receive the free ends of the arms swingably therein, guide rails in the supporting structure to guide the movement of the display panel and movable frame in a vertical plane downwardly until the trunnions receive the free ends of the arms, interruptions in the guide rails to free the arms to swing about the trunnions and carry the movable frame and display panel into a position below and in front of the border.

10. A poster panel comprising a stationary border, a movable frame, a display panel detachably carried by the movable frame, a supporting structure for the stationary border, means connecting the movable frame and the supporting structure to carry the display panel from a display position adjacent the border to a servicing position below and in front of the border, and counterweight means to govern the movement of the movable frame and display panel.

11. A poster panel comprising a stationary border, a movable display panel, a stationary supporting structure for the stationary border, a plurality of arms pivotally secured at one end to the display panel and vertically movable with relation to the supporting structure, a plurality of trunnions in the supporting structure to receive the other ends of the arms to arrest their downward vertical movement and to swing the arms and display panel outwardly and below the border, and counterweight means to govern the movement of the movable frame and display panel.

Certificate of Correction

Patent No. 2,512,515

June 20, 1950

ALEXANDER L. BAUERS ET AL.

It is hereby certified that error appears in the printed specification of the above numbered patent requiring correction as follows:

Column 3, line 54, for "slip" read *slid*; column 7, line 54 and column 8, line 1, strike out the words and comma "a supporting structure for the stationary border,"; column 8, lines 2 and 3, for "for the stationary border, a stationary supporting structure" read, *a stationary supporting structure for the stationary border*; lines 18 and 19, strike out "a supporting structure for the stationary border," and insert the same after "border," in line 17, same column;

and that the said Letters Patent should be read as corrected above, so that the same may conform to the record of the case in the Patent Office.

Signed and sealed this 28th day of November, A. D. 1950.

[SEAL]

THOMAS F. MURPHY,
Assistant Commissioner of Patents.
